(57) **CLAIM**

The ornamental design for a handle for electric toothbrush, as shown and described.

DESCRIPTION

FIG. 1 is a perspective view of a handle for electric toothbrush showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is an enlarged top plan view thereof; and,

FIG. 7 is a bottom plan view thereof.

The broken lines shown in FIG. 7 illustrate portions of the handle for an electric toothbrush that form no part of the claimed design.

1 Claim, 6 Drawing Sheets
